ABSTRACT OF THE DISCLOSURE

A helicopter blade comprising a plurality of bonded components forming a unitary structure having a longitudinally extending portion, a gradual transitional portion and a hollow tube-like portion. The hollow root portion of the blade is secured to a rotor.

The present invention relates to an improved blade for the main rotor of a helicopter or like craft.

As is well known, the rotor blades of helicopters are stressed by considerable oscillatory loads. At present, the material of which such blades are made, while being capable of withstanding high static loads, resist only low oscillatory loads which must, therefore, be kept low if the blade is to have a long life. Moreover, particular care must be devoted to the prevention of stress concentrations, sharp changes of cross-sectional configuration and the like, all of which tend to reduce the life of the blade components. Rotor blades are presently made of different materials, such as wood, metals and plastics, and usually are connected with their yoke by a system including a separable grip member, a bolt and a drag brace. The grip is supported on the yoke by means of feathering bearings, permitting the blade to be turned to allow the adjustment of the blade pitch. Opposed blades are connected with each other by a strap and bolt.

A drawback of the above system is that a concentration of stresses occurs in a number of points, as e.g. in the eye or mountings of the bolt and in the eyes of the drag brace. To withstand such concentrated fatigue stresses, the sections are increased in mass or size which results in substantial localized increases in the stiffness of the blade and of the grip. Thus, the sectional modulus and inertial moment distributed along the blade span does not change gradually but in a discontinuous manner. Such discontinuities in the structure and in the stiffness of the blade lead to local increases in the oscillating stresses.

Other drawbacks are apparent from procedure presently followed in the making of blades for helicopter rotors, as explained hereinbelow.

(a) Wooden blades: Such blades are suitable for small helicopters only since when the rotor sizes are increased, the weight of wooden blades become disproportionately great (i.e. the weight increases proportional to the cube of rotor diameter), and thus extremely heavy blades would be required for large diameter rotors. Moreover, much labor is required in the making of such blades although, conversely, the required equipment is relatively less expensive. Thus, wooden blades are acceptable for a small range of sizes and where mass production does not raise the costs too high. Moreover, a relatively low stiffness is shown by the wooden blades, as a consequence of the low modulus of elasticity of wood. The present

2

trend is conversely directed towards the production of highly stiff blades, capable to better withstand the aero-dynamic and dynamic loads of modern high capacity, powerful helicopters. Finally, the wooden blades, being made of a highly hygroscopic material, undergo an increase in weight, caused by the gradual absorption of air moisture, resulting in deformations which cause difficulties in the balancing of rotors and excessive vibrations,

(b) Metal blades: Presently, nearly all helicopters are equipped with metal blades. The advantages of such blades consist in a rigidity much greater than that of wooden blades, and in the non-hygroscopicity of their material so that they do not suffer from the effects of humidity. To decrease the blade weight to an acceptable limit, metallic blades are made of a load carrying rib structure, covered with thin sheets of an aluminum alloy (usually .016" thick). However, such thin gauge sheets easily suffer from corrosion problems, by which the life of a blade may be significantly decreased. Indeed, when 10 corosions are noticed on the surface, the tendency is to have the corroded areas polished. However, only a limited number of such polishing operations can be made if an excessive decrease in the thickness of the sheet is to be avoided. On the other hand, the corroded surfaces 15 must be polished, both to keep the corrosion from spreading and to prevent the surface from pinholding.

spreading and to prevent the surface from pinholing.

(c) Plastic blades: A number of manufacturers have recently started production of blades for main rotors consisting of structures made of fiberglass fabric impregnated with plastics, such as epoxy resins or the like. Such blades show the advantages of being non-hygroscopic, unlike the wooden blades, and do not require very thin coverings like the thin gauge metal sheets which easily undergo corrosion. However, serious difficulties are encountered in the formation of connecting points, joints or bearing surfaces, as e.g. the feathering bearing housing or the blade root by which the blade is connected to the grip. Moreover, present experience in this field is yet insufficient to know the behavior of such blades under a fatigue stress caused by aging under the action of atmospheric agent (sudden changes of temperature, effects of UV radiations, etc.).

The drawbacks of these conventional blades are avoided by the blade made according to the invention, which also shows, as an added advantage, a gradual variation, without abrupt changes, of the inertial and sectional spanwise modulus.

According to the invention, the blade comprises a plurality of longitudinally arranged components, fitted side by side and crosswise secured to each other, these components being preferably symmetrically located with respect to the longitudinal cross-sectional axis.

respect to the longitudinal cross sectional axis.

As will be described more fully later, the blade may be formed of a first component made of an aluminum alloy in a range of at least 0.118" to 0.157" thick, located 55 to form the leading edge of the blade and designed to act as the main load bearing structure and comprising also the root of the blade; a second component of at least one honeycomb structure preferably of plastic, and with 60 inner cavities, by which the continuity of the blade shape is ensured; a third component consisting of a honeycomb filling, preferably of plastic, and finally a fourth metal component, preferably of aluminum alloy, representing 65 the trailing edge, by which the shape is defined and which contributes, at least partly, to the strength of the assembly, 35

the last component being connected at the root of the blade with the first metal component.

The above components are connected with each other by any conventional bonding process, e.g. by having a film of adhesive, such as the forementioned epoxy resin, interposed between the components, whereafter the assembly may be cured according to the selected adhesive.

The assembly of different components of which the blade is made up, may then be covered with a continuous sheet made of plastic material, also bonded to the inner components along the whole contact surface.

Therefore, the blade according to the invention will not be exposed to the risk of corrosion, except for the metal components of the leading and trailing edges which, however, being relatively thick, may be submitted to a large number of polishing treatments.

The above and further features of the invention will be better appreciated from a consideration of the following detailed description of the invention, which is shown as an illustrative embodiment in the accompanying drawings wherein:

FIG. 1 shows a hub for helicopters with the related connection and a blade of the conventional prior art design.

FIG. 2 shows a blade made according to the present invention, partly sectioned near the root, and

FIG. 3 is a cross-section of the blade, taken on the line III-III of FIG. 2.

The prior art construction shown in FIG. 1 comprises at least one pair of opposed blades 1, secured to a grip 2 by means of a bolt 3 and a drag brace 4. The grip 2 is supported on the yoke 5 of the rotor hub by a plurality of feather bearings 6 which allow the adjustment of the blade pitch by rotation of the grip. The opposed blades are connected to each other by a strap 7 fixed at each end by a bolt 8 through the grip 2. It will thus be apparent how the concentration of stresses mentioned earlier can occur and how these prior art blade constructions are subject to numerous disadvantages.

The blade of the present invention is seen in FIGS. 2 and 3. Only one blade is seen, and only a part of the rotor and hub is shown. Except for the construction of the novel blade, the rotor, feather bearings, etc., remain the same as in FIG. 1.

Referring now to FIGS. 2 and 3, the yoke 5, as shown therein, is substantially similar to the conventional yokes for main rotors, as shown in FIG. 1. Fitted on the yoke 5 are the feathering bearings 6, by which rotation about the longitudinal axis of the blade is allowed, for adjustment of pitch. Also shown is a strap 7 by which the two opposite blades are connected with one another with the aid of a bolt 8 that is threaded through the root of the blade.

The blade according to the invention comprises a first longitudinal metal rib component 9, preferably made of an aluminum alloy, extending spanwise and acting as main load bearing structure. Integral with the rib component 9 and smoothly extending therefrom is the root 9a. Feathering bearings 6 and the bolt 8 for the strap 7 are accommodated in root housing 9a. It is seen that the first member forms a unitary leading edge and root having smooth surface transitional sections.

As shown in FIG. 3, the one-piece rib component 9 has a substantial wall thickness, and is preferably formed as a singular hollow tubular unit with an inner partition wall 9b, acting as resisting and stiffening element. The wall thickness ranges between 0.110" and 0.157".

Bonded to component 9 is a component 10 consisting of a lightweight honeycomb panel, preferably of plastic, and having large inner cavities. The task of the component 9 is to ensure the continuity of the shape of the leading edge and to provide an airfoil surface bonded to a filling element 11 also made of lightweight expanded or honeycomb plastic, but without inner cavities. This element is in turn bonded to a second elongated metal component 12, preferably made of an aluminum alloy similar to

that of leading edge 9. The second metallic component 12 defines the trailing edge of the blade.

As shown in FIG. 2, the metal trailing edge 12 is connected, at its root, with the metal rib structure 9.

The whole blade—except for a part of metal leading edge 9—is covered by a fabric 13 consisting of plastic fibers. The whole assembly of components and covering sheath by which the blade is formed is made into an integral unit by bonding, i.e. by having a film of a suitable bonding agent interposed between the surfaces of the components, whereafter the resulting assembly is cured according to the selected bonding agent.

As can be readily appreciated from the above description, sharp changes in the sections of the blade are avoided by the present invention. Moreover, the present blade is not in need of struttings or bracings since the root of the blade is integral with the metal load bearing rib structure thereof and forms a firm rigid assembly.

Finally, it is also possible to obtain blades of different length and width by merely using different numbers, shapes and arrangements of components, without departing from the spirit and scope of the invention, as defined in the appended claims.

I claim:

1. A helicopter blade for connection directly to a rotor having a hub, said blade comprising in combination, a plurality of bonded components forming a unitary blade structure having

- (A) a longitudinally extending portion;
- (B) a gradual transitional portion; and
- (C) a hollow tube-like portion;

(a) said longitudinally extending portion having a metal rib component formed of a tapered rounded leading edge projection from a vertically disposed integral partition wall, said rounded leading edge and partition wall defining a hollow internal structure for said rib, an outer plastic fiber cover originating near upper and lower surfaces of the partition wall and terminating as a trailing edge of the blade structure, a metallic member disposed within the outer plastic fiber cover at the trailing edge and parallel to said partition wall, a honeycomb plastic filling element having an end surface adjacent said metallic member and an opposite end surface contacting panel members disposed along inner upper and inner lower surfaces of the outer plastic fiber cover, said panel members formed of lightweight honeycomb plastic and positioned to contact the partition wall defining therewith a hollow central blade portion;

(b) said gradual transitional portion having a forward portion continuous with the leading edge tapering toward the trailing edge and joining a forward surface of the root portion; a tapering partition wall continuous with the partition wall of the said extending portion, tapering toward the trailing edge and terminating near a rear surface of the root portion; a tapering metallic member continuous with the metallic member of said extending portion, tapering toward the leading edge and terminating near the rear surface of the root portion forming a V configuration with the tapering partition wall; and a tapering honeycomb plastic filling element continuous with said filling element of the extending portion and having a terminal part filling the said V configuration; and

(c) securing means disposed relative to the hollow root portion for connecting the blade to a rotor.

2. The blade of claim 1 wherein said rib forms the major structural support for said blade.

3. The blade of claim 1 wherein said partition wall has a wall thickness of between 0.118" and 0.157".

4. The blade of claim 1 wherein said securing means is disposed within the hollow root portion.
